UNITED STATES PATENT OFFICE.

JOHN ODEN MORRIS, OF RICHMOND, VIRGINIA, ASSIGNOR TO MORRIS
MOORE, OF DANVILLE, VIRGINIA.

REFRIGERATING SYSTEM FOR CARS.

SPECIFICATION forming part of Letters Patent No. 686,630, dated November 12, 1901.

Application filed February 1, 1901. Serial No. 45,581. (No model.)

To all whom it may concern:

Be it known that I, JOHN ODEN MORRIS, a citizen of the United States, residing at Richmond, in the county of Henrico and State of Virginia, have invented new and useful Improvements in Refrigerating Systems for Cars, of which the following is a specification.

My invention relates to refrigerating systems for cars; and the object of the same is to produce a system which will permit the use of ammonia or other gas in combination with salt brine or gas by itself. Means are also devised for drawing water from the tender of the locomotive for use in cooling the gas, all of which is accomplished by a simple and novel construction to be described in this specification and claimed, and illustrated in the accompanying drawing, forming a part thereof, in which the figure is a vertical longitudinal section of the refrigerating-car, together with fragments of the tender and the adjoining car.

The numeral 1 designates a box-car, which carries the machinery for operating my system. This car 1 is coupled to the tender 2 of a locomotive. A second car, 3, is also coupled to the rear of the car 1. As many cars as make up the train may be connected in a similar manner, as but one car like 1 is required.

In order to provide for circulating the gas and brine through the cars, each car has located in the roof thereof a series of coils of pipe, which are designated by the numerals 4, 5, and 6 in the car 1 and by 4', 5', and 6' in car 3. To run the machinery of my system, a gasoline-engine 7 is permanently secured in the car 1. This engine is provided with a fly-wheel 8 and two pulleys 9 and 10, which are keyed to a main driving-shaft 11. The first belt 12 connects the fly-wheel 8 to a compressor 13, while the pulleys 9 and 10 are connected to a centrifugal pump 14 and a force-pump 15 by belts 16^a and 17^a, respectively.

My system includes in reality three systems all related, but each more or less independent. They are a water-circulating system A, a gas or ammonia circulating system B, and a brine-circulating system C. These systems will be taken up and described in detail in the order named.

The water system A is operated by the

pump 15, which is connected to the water-tank on the tender 2 by a pipe 16. Water-tanks 17 are constructed one in each end of the car 1 and are connected by pipes 18 to the pump 15, which arrangement enables a supply of water to be stored in the car. These tanks 17 can be recharged from time to time by use of the pump 15. A third water-tank 19 is located at one end of the car 1 and communicates with one of the tanks 17 by means of pipes 20. A pipe 21 also connects the tank 19 with the pump 15 and enables a circulation to be maintained in the tank 19 by operating the pump 15. The other tank 17 is in communication with the water-jacket of the compressor 13 by means of pipes 22. A pipe 23, joined to the top of each of the tanks 17, supplies a return of the water to the tender 2 and enables a circulation to be kept up. Each and every one of the pipes is provided with a globe-valve, which enables the flow of water to be regulated. It is easily seen that by means of the pump each of the tanks 17 and 19 can be filled with water and a perpetual circulation of fresh water kept up, as the pipe 23 will conduct the water back to the tender when the tanks 17 have become filled.

The ammonia system B is operated by means of the compressor 13, which has been previously mentioned. This compressor is ordinary in construction and operation, and its cylinder is in communication with an ammonia or gas chamber 24 through the medium of a pipe 25. Connection is also established with the coils 4, 5, and 6 in the top of the car 1 by a pipe 26, joined to the compressor 13. The chamber 24 is connected to a worm 27, located in the tank 19, which worm is oppositely connected to the coils 4, 5, 6 by a pipe 27^a. Connection between the coils in the two cars is made by hose-pipes 28 and 29, which are equipped with couplings 28^a and 29^a, respectively. A reserve ammonia-receptacle 30 is located in the car 3 and connected to the coils 4', 5', and 6' by a pipe 30^a. This receptacle 30 is only used when the cars are uncoupled. When the compressor 13 is operated, the ammonia is drawn out of the coils 4, 5, and 6 and compressed and descends into the chamber 24, from whence it rises through the pipe 24^a, coil 27, and pipe 27^a and expan-

sion-valve 27^b. In passing through the worm 27 it is cooled by the water in the tank 19, and after passing through the valve 27^b it is allowed to expand.

5 The brine system C is operated by means of the pump 14, which is connected on one side to the pipe 25 of the system B and on the other side by a pipe 31 to the bottom of a brine-tank 32. This brine-tank is filled with a 10 strong salt brine supersaturated with ammonia and is joined at its bottom to a pipe 33, which extends upward and is connected to the coils at the top of the car. A pipe 34 connects the top of the brine-tank 32 with the compressor 13. When the pump 14 is operated, a mixture of gas and brine is circulated through the pipes in the direction of the arrows, or 15 brine alone may be circulated by the pump 14.

An electric circuit 35, which includes a cell 20 36 and a switch 37, can be used for starting the engine in the usual manner. A pressure-gage 38 on the compressor denotes the pressure of the gas.

The various systems of circulation in my 25 system trace as follows: In the water system A, which is operated by the pump 15, the water would start from the tender 2, flow through the coupling into pipe 16, through the pipe into the pump 15, through the pump, 30 when it divides and goes through two branches 18, leading to the tanks 17, and through the pipe 21, leading to the tank 19. The overflow from the tanks 17 finds an outlet by means of the pipe 23, and thence returns to the tender 2, thereby completing the circuit. The 35 principal ammonia-circulating system B is run by the pump 13 and starts from the tank 24, into which the liquefied gas is introduced. The ammonia then passes up through pipe 24^a 40 and the worm 27 and is cooled by the water in the tank 19, then through pipe 27^a and expansion-valve 27^b, decreasing the pressure and permitting the expansion of the ammonia. Then, dividing, it passes into the coils 4 5 6 45 and 4' 5' 6' in the two cars, then back through the pipe 26, through which it is drawn by the pump 13, then through the pump 13, where it is liquefied, a part of the heat of compression being removed by the cold water in the 50 jacket on the pump, and runs through the pipe 25 into the reservoir 24, from whence it started. This is the course of the ammonia when the brine-current B is cut out. The 55 brine-circulating system C, which is run by the pump 14, starts from the brine-tank 32, from which the brine is drawn by the pump 14 and forced through the pipe 31^a, through the reservoir 24, where it mixes with the ammonia from the pump 13, then through pipe 60 24^a, through coil 27, where the heat generated by combination of the ammonia and the brine, as well as the heat in the ammonia, will be taken out by the water in the tank 19, then through pipe 27^a and the expansion-valve 27^b, 65 reducing the pressure and permitting the liberation of ammonia. Then, dividing, it passes through coils 4 5 6 and 4' 5' 6', after which it

returns to the tank by way of the pipe 33, the valve 26' being closed.

In connection with brine circulation it is 70 necessary to keep up an auxiliary circulation C' of ammonia through the brine-tank, which circulation is kept up by the pump 13. To do this, the valve in the pipe 26 is first closed and the valve in the pipe 34, which is 75 normally closed, opened. The ammonia to be circulated is that which is released by the brine in the tank 32 after circulating through the coils. This ammonia rises above the surface of the brine in the tank 32 and is drawn 80 through the pipe 34 to pump 13, where it is liquefied and flows out into pipe 25, where it is taken up by the brine and carried through the circulation of the system C, previously described. On the return of the brine to the 85 tank 32 ammonia-gas is once more given off, which gas is drawn out by the pump 13, as above set forth. The circulation C' keeps the brine cool and must always be run in connection with C.

In operation the water system A is run intermittently, as necessity may dictate by the demand for fresh water. When a high degree of refrigeration is desired, the pure-ammonia system B is employed, there being no 90 salt brine permitted in the pipes. When a lesser degree of refrigeration is deemed sufficient or when short of ammonia, the system C, in combination with the system C', is used. In this system the brine must be supersaturated with ammonia. After the systems C and C' have been in use it will be necessary to draw the brine out of all of the systems except the tank 32, which can be cut off from the system B by the valves in the pipes.

I do not wish to be limited as to details of construction, as these may be modified in many particulars without departing from the spirit of my invention.

Having thus described my invention, what 110 I claim as new, and wish to secure by Letters Patent, is—

1. A refrigerating system for cars comprising the combination of an ammonia system and a brine system connected to be operated 115 simultaneously or separately, said ammonia system comprising, a compressor, a worm mounted in a tank provided with water connections, said worm being connected to said compressor, coils located to the roofs of the 120 cars, and connected to said worm and said compressor, and an expansion-valve located intermediate said worm and said coils; said brine system comprising a pump connected to said ammonia system intermediate said 125 worm and said compressor, a brine-tank connected to said pump, said coils, and to said compressor, and a valve located intermediate said brine-tank and said compressor, substantially as described.

2. A refrigerating system comprising the combination with refrigerating-coils, of a compressor connected to said coils, a valve located intermediate said coils and said com-

pressor, a worm mounted in a tank provided with water connections, said worm being connected at one end to said coils and at the other end to said compressor, an expansion-
5 valve located intermediate said coils and said worm, a pump connected intermediate said compressor and said worm, a brine-tank connected to said pump, to said coils and to said compressor, and a valve located intermediate

said brine-tank and said compressor, substantially as described.

In testimony whereof I have hereunto set my hand in presence of two subscribing witnesses.

JOHN ODEN MORRIS.
